CARD PUNCH

Wilfred L. Philbin, Frankfort, and Richard H. Scobell, Herkimer, N. Y., assignors to Remington Rand Inc., Buffalo, N. Y., a corporation of Delaware

Application October 17, 1941, Serial No. 415,386

10 Claims. (Cl. 164—113)

This invention relates to punching machines such as those used in punching statistical cards, and particularly to the mechanisms, in such machines, having to do with the clearing of data set-ups.

The basic structure of the well known "Powers" 90 column alphabetic and numeric punch, in which the present invention has been incorporated, is shown and described in patents Reissue 20,720 and 2,124,178 to W. W. Lasker, issued May 10, 1938, and July 19, 1938, respectively, and 2,160,152 and 2,203,355 to W. F. Kelley, issued May 30, 1939, and June 4, 1940, respectively. The machines illustrated in these patents are such that on any operation involving an automatic carriage return with clearing of the set bars, all the locking slides of both upper and lower zones, which had their associated interponents set in active positions, were retracted. For example, operation of the "Cancel," "Trip," or "Trip intermediate stop" key of the machine disclosed in Patent 2,124,178 caused an automatic carriage return and clearing in both upper and lower zones of the set-bar section of the punch. The present invention permits the punch operator to select any one of three methods of clearing the set bars. First, when using the "Intermediate" stop, he may set the machine so that, on carriage return and clearing operations, only the upper zone will be cleared. Second, he may set the machine so that, on carriage return and clearing operations, only the lower zone of the set bar section will be cleared. Again, he may set the machine so that it functions, as is disclosed in the above patents, to clear both upper and lower zones at once. The machine also functions to clear in both zones of the set bar section when the intermediate stop is positioned on the machine but not in use, that is, when the "trip" key or "cancel" key is operated. These two keys render the intermediate-stop engaging-lug on the carriage ineffective as is old and well known. Thus, it is seen that the present invention lends great flexibility, on clearing operations, to the punch. It is particularly useful with certain accounting systems where it is found desirable to leave certain data in either the upper or lower zone for a plurality of punching cycles.

The main object of this invention is to enlarge the scope of punching machines with respect to the clearing of data set-ups made in those machines.

Other objects and structural details of the invention will be apparent from the following de-

scription when read in connection with the accompanying drawings, wherein

Fig. 1 is a fragmentary front elevation of the machine;

Fig. 2 is a fragmentary sectional elevation showing the carriage, the set bar section and the punch section of the machine;

Fig. 3 is a fragmentary, elevational detail of the carriage and set bar clearing mechanism; and

Fig. 4 is a diagram showing all circuits necessary to an understanding of the present invention.

Referring to Fig. 1, a motor generator 1 is employed to supply current for operating the machine. In addition, it is used to rotate the main shaft 3 through reduction gearing 2. Shaft 3 carries magnetic clutches 4 and 5 which clutches, when operative, couple the main shaft 3 with the back space mechanism and the carriage return mechanism, respectively. The exact construction of these clutching devices will not be described here as it is old and well known. Suffice it to say that a trip magnet 6, when energized, withdraws a blocking finger 8 from the path of a clutch pawl 9 of a single revolution clutch, thus coupling the main shaft 3 to a sleeve 11 upon which the large reduction gear 2 is fastened. The ring magnets of clutches 4 and 5 are also fast to sleeve 11. Thus, if either clutch 4 or 5 is energized, their ring magnets will engage their associated armatures to operate either the back space mechanism or the carriage return mechanism. Clutches 4 and 5 are entirely independent of the single revolution clutch, so that the main shaft 3 need not be rotated to effect back spacing or carriage returning. For specific details of this structure, reference may be had to Fig. 14 of Patent 2,160,152. It is thus seen that trip magnet 6 is used solely for causing rotation of main shaft 3. The main shaft 3 is used to raise and lower the card and punch frame and rotate certain control cams, as is old and well known, to effect punching of a card.

The means employed for entering set-ups into the set bar section of the punch is the same as was previously used and will be described only in brief here. As can best be seen in Fig. 1, keys 12, when depressed, close contacts (not shown) to energize solenoids 13, the cores of which, in turn, actuate Bowden wires 14 to rock bell-crank 15 (Fig. 2), causing depression of links 16. Bell-crank 15 and links 16 are mounted in a carriage 17 which, as is well known, travels step-by-step

over the columns of pins 29 in the set bar section of the punch during setting-up operations. Referring particularly to Fig. 2, the depression of links 16 causes depression of set bars 19. The set bars are held in depressed position by locking slides 20 under the action of leaf springs 21, as is old and well known, alternate locking slides being used to lock the set bars of both upper and lower zones. In the position shown in Fig. 2, the locking slides 20 are retracted allowing clearing of the set bar section.

Previously, the locking slides 20 were retracted, during machine operations which included carriage-return with clearing, by the action of a single retract solenoid which, through a Bowden wire, actuated a bell-crank 23 to lower a roller 24 into contact with interponents 25. The return of the carriage caused the roller 24 to push locking slides 20 seriatim to the inactive position shown in Fig. 2 to release any depressed set bars 19 and allow them to return to their upper or normal positions under action of their associated springs. Thus, before the present invention, any interponent 25, which was moved by roller 24, disabled its associated locking slide 20 during carriage-return and clearing operations. All the interponents were in alignment insofar as their surfaces 26 were concerned so that, during a clearing operation, if the carriage returned ten steps, ten interponents were actuated which, of course, resulted in clearing both the upper and lower zones of those columns of the set bar section concomitantly.

The mechanism of the present invention includes two retract solenoids of which, when actuated, lowers the old roller 24 to active position for clearing and the other of which lowers a similar roller 27 for the same general purpose. Now, however, every other interponent is shaped like the interponent 25 but the alternate interponents 28 have such shapes, shown partially in dotted lines in Fig. 2, that the roller 24 never actuates them. These interponents 28 are actuated only by roller 27 to release the set bars 19 associated with the upper zone of the set bar section while the interponents 25 are now associated only with the lower zone. Thus, if it is desired to release the set bars in the upper zone, the "upper" retract solenoid is energized and, if it is desired to release the set bars in the lower zone, the "lower" retract solenoid is energized. To release the set bars in both zones concomitantly, both retract solenoids are energized and both rollers 24 and 27 are lowered. Referring to Figs. 2 and 3, roller 27 is carried by an arm 30 which is pivoted upon the carriage 17 at 31. The arm 30 is connected to the lower end of a link 32, the upper end of which is connected to a rock lever 33 at 34. Rock lever 33 is pivoted at 35 upon the carriage 17 and is guided in a comb plate 36 which plate is part of carriage 17. One end 38, of lever 33, rests against a Bowden wire terminal 39. A Bowden wire 40, one end of which is secured in the terminal 39, is fastened, at its opposite end, to the core of the "upper" retract solenoid 41 (shown only in Fig. 4). Thus, it is seen that, upon energization of solenoid 41, the Bowden wire 40 is moved to swing lever 33 counter-clockwise (Fig. 3) to depress link 32 and lower roller 27 to active position. In like manner, energization of the "lower" retract solenoid 42 (Fig. 4, only) will move a Bowden wire 43 (Fig. 3) to lower roller 24 by means of well known mechanism.

20

Circuits

Referring to Fig. 4, all the circuits necessary to an understanding of this invention are shown, in a schematic manner for the sake of clarity. Starting at the positive terminal of generator 1, current passes over lead 49 to an on-off switch 45, thence to a repeat-single switch 46 and thence to a main supply lead 47 as is old and well known. A branch 48 of lead 47 supplies power to a timing device T by means of a brush A. This timer is a drum commutator shown developed and is exactly the same as has been used in previous machines and it is mounted upon the main shaft of the machine. This timer is also shown in Fig. 4 of the above mentioned Patent 2,124,178, to Lasker. Every time the main shaft of the machine turns, the timer T rotates with it. Current is supplied directly by lead 47 to a trip key 50 and a trip intermediate key 51 but is supplied to a cancel key 52 through the timer T as will now be described in detail.

Cancel key

When the cancel key 52 is depressed, it accomplishes the following functions:

1. Return of the punch carriage.
2. Clearing of part or all of the set bars.
3. Preventing rotation of main shaft 3 which, consequently, prevents card punching and card feeding.

The mode of operation of the cancel key 52 and its associated parts is as follows: When key 52 is operated, contacts 54 are closed, providing a circuit from positive supply lead 47, through the winding of relay 57, over lead 58, through contacts 54, lead 150, brushes F and E of timer T, lead 151, winding of carriage return magnet 59 and lead 53 to the negative generator terminal. This energizes relay 57 and magnet 59 and attracts armature 60, which, in turn, moves latch 61 counter-clockwise about its pivot 62 to release bell-crank 63 pivoted at 64 (see Fig. 4). Bell-crank 63 (see Fig. 1) is loosely connected by a stud 65 to the "stop bar" 66 of the machine. This bar 66, as is well known, carries a margin stop 67 and an intermediate stop 68 and, on carriage return movements, a lug 69, controlled by the "express" solenoid, strikes one or the other of the stops to shift bar 66 to the left (against spring tension) and thus restores the bell-crank 63 to its normal position shown schematically in Fig. 4.

Whenever the carriage return magnet 59 is energized with the resulting movement of bell-crank 63, contacts 71 and 72 are closed and they remain closed until the carriage, in returning, restores bell-crank 63 to its normal position. The closure of contacts 72 effects a return movement of the carriage by energizing ring magnet 5 (see Figs. 1 and 4), over the following circuit: From positive generator over supply lead 47, lead 74, through the ring magnet or magnetic clutch 5, overlead 56, through contacts 72 and lead 53 to the negative side of the generator. Carriage return magnet 59 is deenergized as soon as the cancel key 52 is opened, but it is unnecessary for the operator to hold the cancel key closed for contacts 72 remain closed, as has been explained, until the carriage has completed its return.

It will be recalled that the retract relay 57 is also energized by cancel key 52 and it is held operated over a locking circuit traced as follows: Positive current over lead 47, through the winding of relay 57, make contacts 75 of

said relay, and lead 76 to the contact 77 of a double-pole, double-throw reversing switch 78. Contact 77 is connected to a contact 79 on the said switch and, in like manner, a contact 81 is connected to a contact 82. Switch arms 83 and 84 are insulated from each other. Thus, it is seen that, when current enters at 77 and the switch 78 is set in its left-hand position, the current will flow directly into arm 83 and out therefrom along lead 86 to upper retract solenoid 41, thus actuating the retract roller 27 (Figs. 2 and 3). The current continues from retract solenoid 41, along lead 87 and through contacts 71 to the negative side of the generator over lead 53. If, however, the switch 78 is set in its right-hand position, then current flows from contact 77 to contact 79 to arm 84 and out over a lead 89 through the lower retract solenoid 42 and thence over lead 87 to the negative side of the generator through contact 71 as described. The operation of solenoid 42 causes the retract roller 24 (Figs. 2 and 3) to be lowered to active position for clearing the lower zone of the set bar section. Thus, it is seen that switch 78 is a reversing switch and can be set to run current from contact 77 to either the upper or the lower retract solenoid. In like manner, when current is supplied to contact 81, the switch 78 may be set to pass the current either via arm 84 to lead 89 or via contact 82 and knife 83 to lead 86. It is to be noted that, if current is supplied concomitantly to both contacts 77 and 81, then both retract solenoids will be energized concomitantly and clearing will occur in both upper and lower set bar zones during a single carriage return. This double supply of current can be brought about either by closing a single-pole single-throw switch 91 or by permitting current to flow through the contacts 75, on the retract relay 57 to contact 77 over lead 76 and also from contacts 75 and lead 55 to "break" contacts 92 (normally closed) on a trip intermediate relay 93, over a lead 94 to switch 91 and contact 81 of switch 78. When the cancel key 52 is operated, the trip intermediate relay is not operated and hence clearing occurs in both zones of the set bar field regardless of the setting of switch 78 or switch 91. In this instance, the carriage will be returned to the margin stop 67 (Fig. 1) because of the action of the well known express solenoid 96 (Fig. 4). The express solenoid, as can be seen operates over a circuit from the positive side of the generator through the on-off switch, repeat-single switch 46 over lead 47 and thence through an intermediate-margin switch 98, over lead 99 through contacts 101 of the trip-intermediate relay 93 and thence over lead 102, through the express solenoid, lead 103, through carriage-breaker contacts 104 and over lead 53 to the negative side of the generator. When the carriage, at the end of its return movement, returns the bell-crank 63 to normal, it has a slight overthrow which results in momentarily breaking contacts 104 and in normalizing an electro-magnetic device, which is operated from the negative side of the generator over lead 103. With regard to the margin-intermediate switch 98, this is shown set in the "margin" position in Fig. 4. If, however, the switch is set in the "intermediate" position, the contact between the supply lead 47 and lead 99 is broken and power can be supplied to lead 99 only through the medium of a trip relay 113, the operation of which will later be

described. It is to be understood that whenever the express solenoid is energized, its core acts through well known mechanism to raise the stop block 69 (see Fig. 1) to a position above the intermediate stop 68 so that, on carriage returns, the carriage will pass on by the intermediate stop 68 and come to rest against the margin stop 67. As the switch is set in Fig. 4, it shows this condition but when it is desired to stop the carriage at an "intermediate" position, switch 98 is thrown to the left breaking its contacts and hence breaking the positive lead 99.

Trip key

15 When the trip key 50 (Fig. 4) is operated, it results in effecting the following machine functions:

1. Rotation of the main shaft through one revolution.
2. Return of the carriage to the margin stop regardless of the setting of the margin-intermediate switch 98.
3. Clearing in both set bar zones regardless of the setting of switches 78 and 91.
4. Punching and ejecting of a card.
5. Feeding a new card into the punch chamber.

The exact manner in which these functions are performed will now be described. When trip key 50 is operated, both of its contacts 109 and 110 are closed (Fig. 4). Closure of contacts 110 closes a circuit from positive generator over lead 49 through switches 45 and 46, over lead 47, through contacts 110, over lead 112, through the winding of a trip relay 113, over leads 111 and 103, and thence through carriage breaker contacts 104 to the negative generator terminal, over lead 53. This energizes relay 113 causing closure of its contacts 114 and 115. Contacts 115 close a holding circuit for the relay which is traced to positive generator over lead 47. The relay will remain energized until the overthrow of the returning carriage breaks contacts 104. Contacts 114 (thus closed) establish a circuit which may be traced as follows: From the positive generator terminal, over lead 49, through switches 45 and 46, lead 47, contacts 114, leads 117 and 99, contacts 101 of relay 93 through the winding of the express solenoid 96, lead 103, carriage breaker contacts 104, lead 53 to negative generator. This energizes the express solenoid regardless of the setting of the intermediate-margin switch 98.

55 Closure of contacts 109, on key 50, establishes a circuit for energizing the trip magnet 6 which may be traced from positive, lead 47 and 48, brush A, segment 118 of timer T, brush C, lead 119, through contacts 109 of key 50, lead 120, through the winding of trip magnet 6 to the negative generator terminal over lead 53. This energizes the trip magnet which results in a single revolution of the main shaft as was previously explained. Movement of the main shaft 3 (Fig. 1) results in punching a card and in feeding a new one into the punch chamber as the punched card is ejected therefrom. Rotation of main shaft 3 also causes rotation of the segments of timer T. It is thus seen that soon after the main shaft begins to rotate, brush C falls away from segment 118 so that even if the trip key were held down it could not supply current to the trip relay 113. It would be unnecessary in view of the described holding circuit through contacts 115.

70 Near the end of the rotation of the main shaft,

a segment 122, of timer T, comes under the brushes D and E. This establishes a circuit for clearing and returning the carriage which may be traced from positive lead 47, lead 54, through the winding of retract relay 57, over lead 58, through brush D, timer segment 122 and brush E over lead 151, through the winding of carriage return magnet 59 and over lead 53 to the negative generator terminal. The energizing of carriage return magnet 59 and retract relay 57 causes energization of both retract solenoids 41 and 42 resulting in clearing in both zones of the set bar section.

There remains but one key to be described. This is the trip-intermediate key 51, and it is with this key that the reversing switch 78 comes into play. Switch 78 when used with the trip-intermediate key permits selective clearing operations as will now be described in detail.

Referring to Fig. 4, key 51 has two contacts 123 and 124. Closure of contacts 123 establishes a circuit traceable from positive lead 47, contacts 123, leads 126 and 120, through the winding of trip magnet 6 and over lead 53 to negative generator. This energizes the trip magnet 6 to start the main shaft rotating. Closure of contacts 124 establishes a circuit traceable from positive lead 47, contacts 124, lead 127, winding of trip intermediate relay 93, lead 103, contacts 104 of the carriage breaker switch, and lead 53 to the negative side of the generator. This energizes the trip intermediate relay 93 which results in opening relay contacts 92 and 101 and closing a pair of contacts 128. Contacts 128 then form part of a holding circuit for the trip intermediate relay 113, current being supplied from positive lead 47 through a lead 129 through contact 128 and winding of the relay to negative current as described above. Opening of contacts 101 causes the express solenoid 96 to be deenergized so that the carriage will return only to the intermediate stop 68 (Fig. 1). Lastly, opening of contacts 92 breaks the circuit through lead 94 to contact 81 on the reversing switch 78. Thus, current may only be supplied to the reversing switch, at a time when the retract relay is energized, through lead 76 to contact 77. Under these conditions, if the reversing switch is set in its left-hand position, current is supplied from contact 77 through arm 83 to the upper retract solenoid 41 and, if the reversing switch is set in its right-hand position, current is supplied from contact 77 to contact 79 and thence through arm 84 to the lower retract solenoid 42. Energizing of the retract relay 57 and the carriage return magnet 59 is accomplished the same as when the trip key 50 is actuated, that is, by rotation of timer T to bring segment 122 under brushes D and E.

From the foregoing, it is seen that current is supplied to the retract solenoids by actuation of the retract relay and that actuation of this relay without actuation of the trip intermediate relay will supply current to both retract solenoids simultaneously through leads 76 and 94. When, however, the retract relay is operated with the trip intermediate relay, the trip intermediate relay breaks lead 94 and permits the reversing switch 78 to be operated to select one or the other of the retract solenoids. When using the trip intermediate relay, the express solenoid is always disabled in consequence of which the carriage comes to rest against its intermediate stop. In this connection, it is to be noted that the intermediate stop 68 (Fig. 1) can be moved far enough to be left to permit a carriage travel that

would allow clearing of an entire zone of set bars.

It is also to be noted that should the need arise for punching a plurality of cards with one set up, the reversing switch 78 provides an additional means for satisfying it. If the switch arms 83 and 84 are set in a middle position, wherein they do not contact any of the points 77, 81, 82, and 79, then operation of either the trip or trip-intermediate keys will cause a punching and ejecting cycle with a carriage return but without erasing any of the set up in the set bars because no current passes from the reversing switch to the retract solenoids.

Should it be found desirable to have the punch function as it did before the present invention, then the single-pole single-throw switch 91 is closed and this enforces concomitant clearing in both set bar zones even when the trip intermediate relay is operated and regardless of any active setting of the reversing switch 78.

While we have described what we consider to be a highly desirable embodiment of our invention, it is obvious that many changes in form could be made without departing from the spirit of our invention, and we, therefore, do not limit ourselves to the exact form herein shown and described, nor to anything less than the whole of our invention as hereinbefore set forth, and as hereinafter claimed.

30 What we claim as new and desire to secure by Letters Patent is:

1. In a machine of the class described, the combination of a plurality of settable machine elements, means operable to set said elements, means for locking said elements in set position, an electromagnetic device operable to disable certain of said locking means, a second electromagnetic device operable to disable other of said locking means, means for establishing a circuit to operate both said disabling means concomitantly, means for breaking the circuit to one of said disabling means to render said disabling means inactive, and means settable to determine which of said locking-disabling means shall be rendered inactive by said circuit breaking means.

2. In a machine of the class described, the combination of a plurality of settable machine elements, means for setting said elements, means for locking said elements in set position, means for disabling certain of said locking means, means for disabling other of said locking means, means for establishing a circuit to operate both said disabling means concomitantly, means for breaking the circuit to one of said disabling means, and means settable to render said circuit breaking means ineffective thus permitting said circuit establishing means to operate both locking-disabling means regardless of the operation of said circuit breaking means.

3. In a machine of the class described, the combination of a plurality of settable machine elements, means for setting said elements, means for locking said elements in set position, means operable to disable certain of said locking means, means operable to disable other of said locking means, means for establishing a circuit to operate both disabling means concomitantly, means for breaking the circuit to one of said disabling means to render said disabling means inactive and switching means through which said circuit establishing means and said circuit breaking means operate, said switching means being settable in one manner to permit said circuit breaking means to render one of said disabling means

ineffective and settable in another manner to enforce the concomitant operation of both of said disabling means regardless of the action of said circuit breaking means.

4. In a machine of the class described, the combination of a plurality of settable machine elements, means for setting said elements, means for locking said elements in set position, means operable to disable certain of said locking means, means operable to disable other of said locking means, means for establishing a circuit to concomitantly operate both of said disabling means, means for breaking the operating circuit to one of said disabling means to render said disabling means inactive, a switch through which said circuit breaking means operates, said switch being settable to control breaking of the circuit to one and the other of said disabling means alternately, and a second switch for rendering said circuit breaking means ineffective to enforce establishment of a circuit to both disabling means.

5. In a machine of the class described, the combination of a plurality of settable machine elements, means for setting said elements, means for locking said elements in set position, means including an electromagnetic device operable to disable certain of said locking means, separate means including an electromagnetic device operable to disable other of said locking means, means including a relay for establishing a circuit to concomitantly operate both of said disabling means, means including a relay for breaking the operating circuit to one of said disabling means to render said disabling means inactive, a switch through which said circuit breaking means operates, said switch being settable to determine which of said disabling means shall be rendered inactive by said circuit breaking means, and a second switch for rendering said circuit breaking means ineffective to enforce simultaneous operation of both of said disabling means regardless of the action of said circuit breaking relay.

6. In a machine of the class described, the combination of a plurality of settable machine elements, means for setting said elements, means for locking said elements in set position, means operable to disable certain of said locking means, means operable to disable other of said locking means, means operable to establish a circuit to operate both of said disabling means concomitantly, means for breaking the circuit to one of said disabling means to render said disabling means inactive, means settable to determine which of said disabling means shall be rendered inactive by said circuit breaking means, and a timing device operable to cause operation of said circuit establishing means and of said circuit breaking means at a predetermined point in a cycle of operation of said machine.

7. In a machine of the class described, the combination of card punching devices, a device for receiving and retaining representations of data to be punched, means for entering said representations into said receiving means, means for initiating a card punching cycle of said ma-

chine, means operable to clear certain of said data representations from said receiving and retaining device, means operable to clear other of said data representations from said receiving and retaining device, means settable in one manner to operate either of said erasing means singly and settable in another manner to operate both of said erasing means concomitantly, and a timing device for supplying power to said settable means to cause operation of said clearing means under control of said cycle-initiating means after said punching devices have acted during a card-punching cycle of said machine.

8. In a machine of the class described, the combination of card punching devices, a device for receiving and retaining representations of data to be punched, means for entering said representations into said receiving means, means for initiating a card-punching cycle of said machine, means operable to clear certain of said data representations from said receiving device, means operable to clear other of said data from said receiving device, means operable to establish a circuit to operate both of said erasing means concomitantly, means for breaking the circuit to one of said clearing means to render it inactive, means settable to determine which of said clearing means shall be rendered inactive by said circuit breaking means, and a timing device for supplying power to said settable means to cause operation of said clearing means under control of said cycle-initiating means after said punching devices have acted during a card-punching cycle.

9. In a machine of the class described, the combination of a plurality of settable machine elements, means operable to set said elements, means for locking said elements in set position, means including a solenoid operable to disable certain of said locking means, means including a second solenoid operable to disable other of said locking means, a relay operable to establish a circuit for actuating both solenoids concomitantly, a second relay operable to break the circuit to be one of said solenoids to render said solenoid inactive, and a switch settable to different positions to determine which of said solenoids shall be rendered inactive by said circuit breaking relay.

10. In a machine of the class described, the combination of a plurality of settable machine elements, means for setting said elements, means for locking said elements in set position, means including a solenoid for disabling certain of said locking means, means including a second solenoid for disabling other of said locking means, a relay operable to establish a circuit for actuating both solenoids concomitantly, a second relay operable to break the circuit to one of said solenoids, and a switch settable to render said circuit breaking relay ineffective to enforce operation of both solenoids regardless of the action of said circuit-breaking relay.

WILFRED L. PHILBIN.
RICHARD H. SCOBELL.
